UNITED STATES PATENT OFFICE

2,277,089

CAR HEATER AND DEFROSTER

Warren Ewald, Racine, Wis., assignor to Young
Radiator Company, Racine, Wis.

Application February 3, 1937, Serial No. 123,844

3 Claims. (Cl. 257—137)

My invention relates to car heaters and also means thereon for defrosting the windshield on the car in which the device is installed.

One of the objects of the present invention is to provide an annular heating core and novel means for supporting the core and the motor and air directing means, whereby the radially entering air is directed rearwardly without excessive friction and whereby a small amount of cool air is directed around the motor to prevent excessive heating.

The principal object of the present invention is to provide a conventional blower fan having additional means thereon whereby a desired quantity of heated air may be conducted to and discharged against the windshield in a suitable manner to thereby prevent frosting.

One of the objects of this invention is to provide a novel core assembly whereby the core may be made up in two sections, each section having two portions of a header attached thereto, whereby after the sections are completed as individual units, they may be made into a unitary core by simply bonding the two portions of the header together.

Another object of the present invention is to provide a unit heater of the class described which is simple, light, neat and easily manufactured at low cost.

To these and other useful ends my invention consists of parts and combinations thereof or their equivalents as described and claimed and shown in the accompanying drawings in which:

Fig. 1 is a front elevation of my improved car heater taken on line 1—1 of Figure 2.

Fig. 2 is a partially sectioned elevation of the device taken on line 2—2 of Figure 1.

Fig. 3 is a front elevation of the complete core.

Fig. 4 is a plan view of one of the core units viewed from the header side of the core.

Fig. 5 is a section taken on line 5—5 of Figure 3.

Fig. 6 is a front elevation of the device illustrating the tubes and nozzles used for directing the heated air against the windshield.

As thus illustrated the core of the device comprises tubes 10 which are formed in a semi-circle having spaced fins 11 as is the custom in radiators of the class. On the ends of one set of tubes I position header members 12—12 and on the other set of tubes I position header members 13—13. Header members 13 are provided with flanges 14—14 which snugly embrace header members 12, being bonded thereto. On the front side of header members 12 I provide flanged openings 15—15 which are adapted to tightly em-

brace inlet and outlet tubes 16—16, the tubes being bonded to the flanged openings in the usual way. Thus it will be seen by referring to Figure 3 that hot water, steam or other heating or cooling liquids or gases may pass from one of the tubes 16 through the two sides of the core in multiple and out at the other tube.

The plan in the present invention is to draw the recirculated air from the car inclosure inwardly between the fins and then rearwardly, exhausting the air into the car inclosure as illustrated in Figure 2 by curvilinear arrows.

I provide a rear holding plate 20 being pressed from a flat piece of steel in the form shown in Figure 2. The motor 21 is secured to the center of this plate by means of bolts 22—22 and cushion washers 23—23. Pockets 24—24 are formed in member 20 to thereby provide supporting legs which are held against cowl board 25 by means of bolts 26—26. Thus member 20 is securely held to the cowl board and motor 21 is securely held to member 20, having means to deaden any sound which might otherwise be transmitted from the motor to the cowl board.

Member 20 provides a surface as at 30 against which to bind the core as indicated. I provide a thin plate 31, the inner portion being cone shaped as at 32, thus to prevent the hot air from contacting the motor. A narrow annular opening as at 33 is provided which leaves room enough if desired for the passage of cool air which may enter orifices 34, the object being to permit a small amount of cool air to pass around the motor, thus to further insure against excessive heating of the motor.

I provide means for recirculating the air through the core and for supplying air to the defroster as follows:

Plate 36 is secured to member 30 by means of bolts 37—37 the radiator core being securely held therebetween. This plate is provided with a rearwardly extending flange 38 and a rearwardly extending flange 39 as indicated in Figure 2. Flange 39 is provided with an inwardly extending flange 40 having an opening which is preferably slightly larger than the inside diameter of the core as illustrated in Figure 2. I provide an annular ring 41 which is secured to flange 40 and having an inwardly extending flange 42 and an opening the same diameter as the opening in flange 40.

I provide a housing 45 having a circular opening which is preferably slightly larger than the opening in flanges 40 and 42 into which I mount an air directing means which comprises a cir-

cular ring 47 and air directing louvers 48. Ring 47 is suitably centered on the housing whereby it may easily be turned to the right or left for directing the air as desired. In order to hold the desired adjustment I provide bolts 50-50 having springs 51-51, the springs resting on clips 52-52 the inner ends of which rest on ring 47. Spring 51 provides sufficient pressure on clips 52 to prevent the air directing means from moving except when manually directed.

Housing 45 fits snugly over flange 38 and is secured thereto by means of suitable bolts as indicated in Figure 2.

I provide the usual fan blades 60 having a conventional hub and being secured to the shaft 15 of motor 21, whereby when the motor turns air will be drawn into the fan through the core and discharged under louvers 48 in the desired direction, the air being heated as it passes through the core.

In the past it has been the custom to provide a separate fan and motor with which to secure sufficient pressure to the air for defrosting purposes. In some devices the air for this fan is supplied from the discharge side of the heater and in other instances the fan is caused to blow a blast of interior air against the windshield. The latter device is unsatisfactory because of insufficient heat and the former is unsatisfactory because of the first cost and the inconvenience and cost of operating two motors instead of one.

In the present invention flanges and members as described provide an annular chamber 65. Plates 66 are preferably formed as an integral part of the fan blades 60 each being held concentric with the motor. I provide two annular rings 66^a-66^b to which members 66 are suitably secured thus providing means for mounting a number of suitably spaced blades 66^b. The outside wall of chamber 65 is shaped as illustrated in Figure 1, making it suitable for a centrifugal type of fan housing. Thus it will be seen that members 66 and 66^b will act centrifugally to create a vacuum and draw some of the heated air into chamber 65 and cause it to be discharged from the outlets 67-67. Outlets 67 are provided with suitable, preferably flexible tubes 68-68 on the ends of which I secure flattened nozzles 69-69 which are suitably positioned whereby the discharged air will impinge the windshield and thus the heated air will prevent the formation of ice, frost or sleet on the windshield.

The principal object of the present design is to provide sufficient velocity of heated air at the nozzle outlets to prevent the formation of ice,

frost or sleet on the glass in the coldest weather.

In the present invention I have for convenience illustrated fins 11 as a means of extending the heat exchange surface. Other shaped fins may be supplied, for example, the corrugated type which rests between tubes. For convenience I have also disclosed each core as having 6 tubes. Tubes and fins obviously may be of various designs and numbers and variously positioned.

Clearly in the design shown the fan and motor may be differently positioned. An entirely different core may be used and a separate cage fan may be secured to fan blades 60. Thus it will be seen that many changes may be made without departing from the spirit and scope of the invention as recited in the accompanying claims.

Having thus described and shown my invention, I claim:

20 1. In a heater, a core, a casing for the core, having main and auxiliary air discharge openings, an air impeller of the axial delivery type adapted to move air through the core, said impeller having a plurality of blades, and an annular series of blades carried by said impeller blades near their peripheries and constituting a blower of radial delivery type, said last mentioned blades being in number substantially greater than the number of blades of said axial delivery type impeller, said blower being adapted for forcing air through said auxiliary opening, and means for rotating said impeller.

35 2. A unit heater having an outer casing having a main delivery opening, a radiator in the casing, a fan of the propeller type for forcing air through said radiator and then through said main opening, and an impeller type of fan including a fan chamber adapted to receive air from the radiator and having oppositely disposed delivery outlets through which the impeller forces air by centrifugal action.

40 3. A unit heater having an outer casing having a main delivery opening, a radiator in the casing, a fan of the propeller type for forcing air through said radiator and then through said main opening, and an impeller type of fan including a fan chamber adapted to receive air from the radiator and having oppositely disposed delivery outlets through which the impeller forces air by centrifugal action, said impeller being mounted on and at the periphery of said propeller.

55 WARREN EWALD.
